LIFE SAVING DEVICE

Filed April 22, 1930

Fig. 2.

Inventor

Louis Paston

By His Attorney John J. Lynch

UNITED STATES PATENT OFFICE

LOUIS PASTON, OF NEW YORK, N. Y.

LIFE-SAVING DEVICE

Application filed April 22, 1930. Serial No. 446,420.

This invention relates to life saving devices and in particular to a construction adapted for use at the seashore or in a swimming pool.

A particular object of my invention is to provide a net construction which is capable of being raised to lift the person in distress so far out of the water that there will be no danger of their being drowned.

A still further object of my invention is to provide in connection with a raisable net of the character referred to, a means whereby a siren is sounded prior to and during the raising of the net and at the same time, an annunciator at a remote point is arranged to give an alarm so that it can be determined from a headquarter station just which net has been operated so that emergency service may be rendered at the point where it is needed without loss of time.

A still further object of my invention is to provide a construction which may be applied to swimming pools, shores of lakes or seacoast and which affords a measure of protection not heretofore possible to persons in danger of drowning.

With the foregoing and other objects in view, which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

In the accompanying drawings:

Figure 1 is a view in sectional elevation showing the application of my life saving device to a shore or swimming pool together with a diagrammatic illustration of the alarm sounding device and annunciator, and

Figure 2 is a top plan view of the construction illustrated in Figure 1 showing the arrangement of the net which is drawn up to raise the person in distress out of the water.

Referring to the drawings in detail, 5 indicates the bottom of a swimming pool or seashore to which my invention has been applied, the invention contemplating the use of

hollow posts 6 in which are pivoted the upper and lower pulleys 7 and 8 respectively, the pulleys being mounted on the axles 9 which pass through the diametrically opposite sides of the hollow post 6, which may be of square or cylindrical shape in cross section, depending upon the conditions under which they are employed. The pulleys 7 and 8 are arranged to have passed thereover, the cables 9—A and 10, which, at one end are secured beyond the water by the stakes 11 and at their opposite ends are arranged to be wrapped about the winding drums 12.

These winding drums 12 are carried on the opposite ends of a motor shaft 13 which passes through the motor 14 which is operated from a suitable source of current 15. The cables 9—A and 10 are connected by the netting 16, the netting extending substantially to the post 6 and being turned up slightly at the outer end so that in raising, the edge of the net would catch anyone that was in distress within the posts, which, of course, would define the safety limits of bathing.

The continuation of the cables 9—A and 10, as indicated by the numeral 17 and 18 respectively, pass upwardly over the pulley 7 and down and around the pulley 8 and back along the bottom of the pool or beach bottom, to and around the drums 12 to which their ends are secured so that operation of the drums 12 by the motor will cause a drawing in of the cable extensions 17 and 18 with the result that a tension will be put on that portion of the cables 9—A and 10 and the net will be raised as indicated by the numeral 20 in Figure 1, completely out of the water so that a person in distress is lifted clear of the water with a minimum of time and effort.

When a person is in distress, it would simply be necessary for some observer to operate the handle 21 on the alarm box 22 with the result that the siren 23 would be sounded and the motor 14 would begin to operate. At the same time, a distant annunciator 24 would indicate which station the net was being raised at and emergency could be rushed to such point in the event that it was needed.

When the siren 23 is sounded, others swimming in the vicinity of the particular net at which the siren was sounded, would get from over the net and when raised, it would lift the person that was in distress clear of the water, as before mentioned, after which they could be removed from the net to safety.

If desired, the net could be weighted along its edges so that it would not interfere with the bathers, and would lie flat on the bottom 10 and out of the way.

It is evident, therefore, that my improved construction may be applied to shores, swimming pools or other swimming places and the device may be operated by anyone and the services of a lifeguard can be dispensed 15 with.

Further, the device having few parts and being simple of operation may be readily set 20 up or taken down and may be used in batteries and connected with a central emergency station to which a signal is given to indicate the net being raised.

The use of an automatic trip device is contemplated which will stop the motor when 25 the net is raised above the surface of the water. Means also will be employed for reversing the operation of the motor to permit net to be lowered to its original position, which means may also be automatically controlled in any well known manner.

While I have illustrated and described my invention with some degree of particularity, I realize that in practice various alterations 35 therein may be made without departing from the spirit of the invention or the scope of the appended claims.

What I claim is:—

1. A life saving device comprising a plurality of posts, an upper and a lower pulley 40 in each of the posts, cables passing under the lower pulley and over the upper pulley, anchors for the ends of the cables, a net connecting the cables from their points of anchorage to a point adjacent the posts, and means for winding up the free end of the cables.

2. A life saving device comprising a plurality of posts, an upper and a lower pulley 45 in each of the posts, cables passing under the lower pulleys and over the upper pulleys, anchors for the ends of the cables, a net connecting the cables from their points of anchorage to a point adjacent the posts, drums for reeling in the free ends of the cables, a motor for operating the drums, and a signal 55 associated with the motor.

3. A life saving device comprising a plurality of posts, an upper and a lower pulley, 60 in each of the posts, cables passing under the lower pulleys and over the upper pulleys, anchors for the ends of the cables, a net connecting the cables from their points of anchorage to a point adjacent the posts, drums for reeling in the free ends of the cables, a 65

motor for operating the drums, a motor circuit, an audible alarm, a visible indicator and said alarm and indicator both being connected with said motor circuit.

In testimony whereof, I have signed my name to this specification, this 18th day of April, 1930.
